UNITED STATES PATENT OFFICE.

CYRUS L. BUNDY, OF JERSEY CITY, NEW JERSEY, AND JULIUS J. ACKER, OF HORTON, KANSAS, ASSIGNEES TO COMMONWEALTH STEEL COMPANY, OF ST. LOUIS, MISSOURI, A CORPORATION OF NEW JERSEY.

CAR DRAW-BAR CARRY-IRON.

1,079,633.

Specification of Letters Patent. Patented Nov. 25, 1913.

Application filed November 19, 1909. Serial No. 528,990.

To all whom it may concern:

Be it known that we, CYRUS L. BUNDY and JULIUS J. ACKER, citizens of the United States, residing, respectively, at Jersey City, in the county of Hudson and State of New Jersey, and at Horton, in the county of Brown and State of Kansas, have invented a new and useful Improvement in Car Draw-Bar Carry-Irons, of which the following is 10 a specification.

Our invention relates to a car draw-bar carry-iron, and has for its object to prevent the sliding and consequent friction of the draw-bar in the direction of its longitudinal movement on the carry-iron, and to automatically return the draw-bar to its normal central longitudinal position on removal of the lateral stress therefrom.

It consists in features of novelty as hereinafter described and claimed, reference being had to the accompanying drawing forming part of this specification, whereon,

Figure 1, is a front elevation of our improved car draw-bar carry-iron as applied 25 to the platform front end portion of a metallic car underframe; Fig. 2, a vertical transverse section through the carry-iron, and corresponding longitudinal section through the platform (broken away) on line 2, 2, in Fig. 1, and Fig. 3, an enlarged view corresponding to Fig. 1 of the carry-iron, shown partly in vertical longitudinal section on line 3, 3, in Fig. 2.

Like letters and numerals of reference 35 denote like parts in all the figures.

a represents our improved car draw-bar carry-iron which in the present case consists preferably, of a yoke having its arms 1 vertically arranged and formed at their 40 upper free ends with preferably, outwardly projecting journals or trunnions 2 which are supported in bearings 3 removably fixed by bolts (or otherwise) 4 to a suitable member or appendage of the car underframe according 45 to the type and construction of the latter, in the present case to the underside of the platform *c* forming part of a metallic car underframe, the yoke *a*, being adapted to swing forwardly and rearwardly about its 50 journals 2 as hereinafter more particularly referred to.

On the horizontal cross bar 1' of the yoke *a*, is adapted to slide to and from each arm 1, a block or chair 5 having its top face

x of a convex curvature transversely and 55 adapted to support the draw-bar *d*, which when moved forwardly or rearwardly from its normal position (corresponding to the vertical position of the yoke *a*) in the "draft" and "buffing" operations of the 60 draft-gear, constrains and swings the yoke *a*, with its block 5 in a corresponding direction about its pivots 2, 3, without sliding on the block 5, the curvature of the bearing face *x* being such that the draw-bar *d* 65 in whatever position it may be, is maintained at a constant level and horizontally tangential to its point of contact with the block 5.

Projecting from the bearing face *x* of the 70 block 5 are two opposite upright brackets 6 between which the draw-bar *d* rides and is guided in close proximity thereto. The block 5 is formed on its underside, preferably in the middle, with a depending lug 7 75 which passes through a suitably shaped opening 7' in the cross bar 1' of the yoke *a*, the opening 7' being somewhat longer than the lateral play of the draw-bar *d*, and from each end of the cross bar 1' depends a rib (or lug) 8 through which, and 80 freely through the lug 7, is passed horizontally a bolt 9 fixed at its ends against the ribs 8 by a head 10 and nut 10' as shown, or in any other suitable manner. 85

Around the bolt 9 between each rib 8 and the corresponding side of the lug 7, is a spiral spring 11, by which, on the lateral movement of the draw-bar *d* with its bearing block 5 along the cross bar 1', the draw-bar *d* on removal of the lateral stress therefrom, is automatically returned to its normal central position. 90

From the above it will be observed that the carry-iron has a swinging motion in the 95 direction of the pulling and buffing movements of the draw-bar, the convex face of the saddle block 5 practically maintaining the draw-bar in the same horizontal plane during such movements, and that the saddle block which supports the draw-bar has a movement at an angle to the direction of the movement of the draw-bar in its pulling and buffing actions so as to accommodate the swing of the draw-bar on curves, means 100 being provided to restore or center the saddle block so as to maintain the draw-bar 105 normally in central position.

What we claim as our invention and desire to secure by Letters Patent is:—

1. The combination in an under frame, of a carry-iron pivotally suspended therefrom, a saddle block movably mounted on the carry-iron, and having its supporting face convex means for yieldingly holding said saddle block in a central position to guide a draw-bar arranged in said saddle block. 45
2. In a car draw-bar, a carry-iron pivotally suspended from the car, a support for the draw bar slidable on the carry-iron and having its supporting face convex lengthwise of the said bar, and a spring interposed between each side of the carry-iron and the said support. 50
3. The combination of a pivotally mounted carry-iron, and a saddle block for supporting a draw-bar, which saddle block is yieldingly mounted to move transversely upon said carry-iron. 55
4. A draw bar hanger comprising the combination of a swinging support, a saddle block carried by said swinging support and adapted to move transversely thereupon, and yielding pressure means interposed between the swinging support, and the saddle block for maintaining the latter in a central position upon said swinging support. 60
5. In a car including a draw bar, a support therefor, which support is mounted to swing longitudinally, and a transversely movable member mounted on the longitudinally swinging support and adapted to engage the draw-bar. 65
6. In a car including a draw bar, a support therefor, which support is mounted to swing longitudinally, a transversely movable member mounted on the longitudinally swinging support and adapted to engage the draw-bar, and means for normally maintaining the transversely yieldable member in a central position upon the longitudinally swinging support. 70
7. In a car construction including a draw-bar, a saddle block for supporting the draw bar, said saddle block being movable in the direction of the buffing and pulling movements of the draw-bar, means for supporting said saddle block in position, so as to permit the lateral swing of the draw-bar, and yielding means for centering said saddle block. 75
8. In a railway car, members depending from the underframe and provided with openings forming journals, a carry-iron having its ends pivoted in said journals, a rounded bearing portion on said carry-iron for supporting a draw-bar and flanges at the extremities of said bearing portion for guiding the draw-bar thereon. 80
9. In a device of the class described, depending members suspended from the car, a bearing member supported between said depending members for movement transversely of the car, said bearing member being provided with a convex bearing surface for supporting the draw-bar, said bearing member being also provided with projections between said convex bearing surface and the depending members for retaining the draw-bar against lateral movement on the bearing surface. 85
10. In a device of the class described, supporting members depending from a car, a carry iron pivoted in said members and having a rounded bearing surface adapted for rocking coöperation with a draw bar. 90
